DE FOREST B. CATLIN

THERAPEUTIC DEVICE

Filed Oct. 20, 1924

UNITED STATES PATENT OFFICE.

DE FOREST B. CATLIN, OF BOSTON, MASSACHUSETTS.

THERAPEUTIC DEVICE.

Application filed October 20, 1924. Serial No. 744,580.

The present invention is a therapeutic device for applying ultra-violet light, or similar radiation, to affected tissue and in particular to the teeth sockets in the human 5 jaw.

It has been found that ultra-violet rays have a curative effect upon abscesses or other infections which form at the roots of teeth, a diseased condition known generally as dento-alveolitis. As the blood corpuscles are relatively opaque to ultra-violet rays, it is usual to apply pressure when subjecting an affected part to ultra-violet rays so as to "dehaematinize" the tissue, or in other 10 words, force the blood out of the path of the light rays. The requisite pressure can be exerted by a quartz rod or applicator, through which the therapeutic rays are conducted from the source, as for example an 15 electric arc to the tissue to be treated.

Heretofore the pressure has been applied by the effort of the operator who held the applicator in his hand and pressed it upon the region of the jaw to be treated. The 20 necessity of applying pressure while manipulating the other part of the apparatus distracted the attention of the operator from the medical aspect of the case and interfered somewhat with the course of the treatment. 25 In accordance with my invention, I have provided an apparatus whereby the affected part can be held between a plurality of quartz applicators which are so shaped and supported that the requisite pressure is applied to the part by the applicator members, and automatically maintained, for example, by a spring pressing the terminals of the members toward each other by a 30 spring. The support for these applicators is constructed to permit of its rotation through an arc so as to position the bent ends of the quartz rods for convenient use with either the lower or upper jaw of a patient. 35 The novel features of my invention will be pointed out with greater particularity in the appended claims.

An apparatus embodying my invention is shown in the accompanying drawing in which Fig. 1 is a side elevation of an applicator mounted on a casing in which is located an arc device; Figs. 2 and 3 respectively are a front elevation and a plan view, the latter being partly in section; and Figs. 4 to 6 are pictorial representations of the teeth with relation to the applicators. 45

Referring to the drawing, the device com-

prises a water-cooled casing 1 in which is provided a source 2 of ultra-violet rays, such as a device for operating a mercury arc within a quartz bulb. Upon the casing are mounted the applicator rods 3 and 4 consisting of fused quartz which conduct the rays emitted by the arc device 2 and passing through the quartz windows 5 and 6. The rods 3 and 4 are frictionally held within 50 tubular holders or sleeves 7, 8 which in turn are mounted upon a knurled cylindrical base 9. This base rotatably engages with the cylindrical rim 10 formed on the side of casing 1. This knurled base 9 is locked to 55 the rim 10 by lugs 11 and 12 which engage with slots in ears 13 and 14 in a strap spring 15, shown in dotted lines in Fig. 2. The spring 15 is held in a groove 16 in the rim 10 and is applied and removed by the 60 head 17.

The applicator rod 4 is urged toward the applicator rod 3 by a leaf spring 18 which is affixed to the holder 8 and the base 9, and automatically maintains compressing 65 pressure on an affected tissue interposed between the opposed terminals of the rods. The spring 18 may be released by a hand lever 19 which projects outwardly from the holder 8 so as to swing the holder about the 70 point 20 as a pivot when pressure is applied to the lever 19 by the operator.

The applicator base 9 may be revolved 75 180 degrees upon the rim 10 so as to swing the bent ends of the applicators downwardly as in Figure 4 and in Fig. 2 by full lines, and upwardly as shown by Figure 5, and by dotted lines in Figure 2. The rotation is retarded somewhat by the spring strap 15 acting as a brake so as to avoid any 80 looseness between the rim 10 and the base 9 under normal operating conditions, but allows it to rotate when some force is applied. The lever 19 is made of two parts pivoted at 85 21 to permit its being doubled back on itself out of the way of the casing 1 when the applicators are rotated. A stop 22 preferably is provided on one of the holders which bears against the cooperating holder and keeps the ends of the quartz rods out of contact when not in use to prevent injury to 90 the tips by chipping or abrading.

The outer ends or terminals of the applicator rods are bent in two planes substantially at right angles to bring them into 95 convenient juxtaposition so that the affected tissue may be conveniently held under pres-

sure between the tips of the applicators as shown in Figs. 4 and 5. These two figures represent teeth at 23 at the roots of which an ulceration has formed as indicated at 24.

5 The ends of the applicators 3 and 4 press against the surrounding tissue 25 squeezing out the blood and permitting the ultra-violet rays to reach the infected part. As shown in Fig. 6 at 26, the point of contact 10 and pressure of the applicators to advantage also may be positioned between the teeth at the junction of the crown with the root as it is at these points that the infection begins.

15 By the described apparatus the dosage of ultra-violet rays is doubled as two applicators are used instead of one. Both the area of application and the amount of ultra-violet are doubled. Hence, the time required for a given treatment may be reduced to one-half. Further, the pressure is automatically maintained without care by the operator. By the shape of the applicators difficultly accessible places in both the 20 lower and the upper jaws can be readily treated. Of course, other anatomical parts may be treated as described in connection with the human jaw.

What I claim as new and desire to secure 30 by Letters Patent of the United States, is:

1. A therapeutic device comprising a light source, a plurality of quartz members having opposed terminals, means for mounting said members with respect to said light 35 source, to permit light to be conducted through the members to a tissue interposed between the terminals, and to permit move-

ment of the terminals toward and from each other, and means for applying pressure to the members to compress the interposed tissue, the last-mentioned means having provisions for automatically maintaining the compressing pressure. 40

2. A therapeutic device comprising a light source, cooperating rods consisting of fused quartz, means for mounting said rods with respect to said light source to permit light to be conducted through said rods upon a part to be treated and means for urging said rods toward one another to 45 apply pressure upon a part while receiving light through said rods from said source. 50

3. A therapeutic device comprising a source of ultra-violet light, a plurality of quartz rods having bent ends, means for holding said rods into operative relation to said light source, while bringing said bent ends into juxtaposition, means for applying pressure to a part being treated while positioned between said bent ends and means 55 for releasing said pressure. 60

4. A therapeutic device for treating tissue with ultra-violet rays comprising a container, a source of ultra-violet radiations in said container, a rotatable support mounted 65 on the container, a pair of quartz rods terminating in bends shaped to cause their tips to be juxtaposed when said rods are mainly parallel, a spring mounted to press the tips of said rods toward one another, and a 70 handle for releasing said spring pressure.

In witness whereof, I have hereunto set my hand this 15th day of October 1924.

DE FOREST B. CATLIN.
